(57) **CLAIM**

We claim the ornamental design for a landscape edging, as shown and described.

DESCRIPTION

FIG. 1 is a perspective view of a landscape edging showing the claimed design.

FIG. 2 is a top view of the landscape edging of FIG. 1.

FIG. 3 is a bottom view of the landscape edging of FIG. 1.

FIG. 4 is a first end view of the landscape edging of FIG. 1. The opposing second end is a mirror image of the first end. FIG. 5 is a front view of the landscape edging of FIG. 1; and,

FIG. 6 is a rear view of the landscape edging of FIG. 1.

The landscape edging is shown with a symbolic break in its length indicated by the dot-dash-dot lines. The appearance of any portion of the article between and including the dot-dash-dot lines forms no part of the claimed design.

The dash-dash-dot broken lines in the figures depict portions of the article that forms no part of the claimed design.
